CLAIM

The ornamental design for cane bottom region, as shown and described.

DESCRIPTION

FIG. 1 is a front view of a cane showing my new design, the bottom portion of the cane in solid lines having the same appearance on all sides;

FIG. 2 is an enlarged, fragmentary side view of a first embodiment of the bottom region of the cane;

FIG. 3 is a top view of the bottom region thereof;

FIG. 4 is a bottom view thereof;

FIG. 5 is a front view of a second embodiment thereof;

FIG. 6 is an enlarged fragmentary side view thereof;

FIG. 7 is a top view thereof; and,

FIG. 8 is a bottom view thereof.

The dimples depicted on the surface of the spherical ball portion of the cane bottom region are understood to be uniformly repeated throughout the surface they are depicted upon.

The broken lines in FIGS. 4 and 8 represent the boundaries of the claim, and broken lines in FIGS. 1 and 5 depict unclaimed environment. None of the broken lines form a part of the claimed design.
